ABSTRACT OF THE DISCLOSURE

A well cap device for closing the upper open end of a cylindrical well casing and comprising a well cap base having an opening therein and adapted to be mounted on the upper end portion of a well casing. A well cap cover detachably mounted on the well cap base and an annular sealing element interposed between the well casing and the well cap base and progressively urged in sealing relation therebetween as the well cap base is urged downwardly into position on the well cap casing.

SUMMARY OF INVENTION

The upper open end of a well casing for a water well is normally closed by a well cap device and these commercial well cap devices vary in construction. These well cap devices must be arranged and constructed to provide an effective seal, but also must permit access to the interior of the well casing. Many of the commercial well cap devices are comprised of a plurality of parts and while in some instances do provide a suitable seal, these commercial devices are arranged and constructed so that it is difficult to gain access to the interior of the well casing without substantially disassembling the well cap device. Further, the multiplicity of parts of such commercial well cap devices renders them expensive to produce.

It is therefore a general object of this invention to provide a novel well cap device of simple and inexpensive construction, which includes a well cap cover when applied to the well casing may be readily removed therefrom without requiring disassembly of the entire well cap device. More specifically, it is an object of this invention to provide a well cap device for a well casing which is comprised of a well cap base and a well cap cover and a suitable sealing element interposed between the well cap base and the well casing in a manner to provide a highly effective seal therebetween.

A BRIEF DESCRIPTION OF THE FIGURES
OF THE DRAWING

FIG. 1 is an exploded perspective view of the novel well cap device,

FIG. 2 is an elevational view of the upper end portion of a well casing with the annular sealing element applied thereto,

FIG. 3 is a view similar to FIG. 2 but illustrating the interrelationship of the annular sealing element and well cap base as the latter is initially applied to the well casing,

FIG. 4 is a view similar to FIG. 3 but illustrating the well cap base and sealing element secured in place on the well casing, and

FIG. 5 is a side elevational view similar to FIGS. 2, 3 and 4 but illustrating the well cap device completely assembled and secured in place on the well casing.

DETAILED DESCRIPTION OF THE INVENTION

Referring now to the drawings and more specifically to FIGS. 1 and 5, it will be seen that one embodiment of the novel well cap device, designated generally by the reference numeral 10 is there shown. The well cap device

2

10 is for use in closing the open upper end of a well casing 11, such as those used in water wells. Ordinarily, the well casing 11 projects upwardly above the surface of the ground approximately twelve to eighteen inches and this open top must be closed in sealing relation with respect to the exterior to prevent the entrance of pollutants into the well casing. A conventional electrical operated pump will be positioned within the well casing 11 adjacent the water table for pumping water upwardly through the conduit in a well-known manner.

The well cap device 10 includes a well cap base 12 which as shown is of generally oval flat configuration and which has a relatively large circular opening 13 therein. It will be noted that the opening 13 is offset with respect to the center of the well cap base and this opening has a diameter slightly larger than the exterior diameter of the well casing 11 to permit the well cap base to be positioned over the well casing. The well cap base has an upturned rather shallow peripheral flange 14 integrally formed therewith and presenting a flat upper surface. The peripheral flange 14 has a plurality of threaded apertures 15 therethrough. It will also be noted that the well cap base 12 has a smaller opening 16 therethrough, the function of which will be set forth more fully hereinbelow.

25 The well cap base 12 has a downwardly projecting generally cylindrical flange 17 integrally formed therewith and disposed in substantially concentric relation with respect to the opening 13. It will be noted that the inner circumferential surface 18 of the cylindrical flange 17 is uniformly tapered downwardly and outwardly from the lower surface of the well cap base. It will further be noted that the upper end of the inner circumferential surface 18 of the cylindrical flange 17 has a diameter slightly larger than the diameter of the opening 13 so that the 30 downwardly facing shoulder 19 is formed thereat.

The well cap device 10 also includes a well cap cover 20 which as shown is of generally concave convex configuration and when detachably secured to the well cap base has its convex surface presented downwardly. The 35 well cap cover 20 is provided with a substantially flat top wall 21 having a continuous generally oval shaped peripheral wall 22 integrally formed therewith and projecting downwardly and flaring slightly outwardly therefrom. The peripheral wall 22 has a plurality of recesses 23 formed therein so that generally horizontally oriented substantially flat attachment portions are formed adjacent the lower peripheral portions of the peripheral wall. These attachment portions are each provided with an aperture 25 therethrough to accommodate the bolts 26, the latter being provided with suitable washers 27 and threadedly 40 engaging the threaded apertures 15 in the well cap base 12. A suitable gasket 28 is also provided and is interposed between the lower peripheral flat edge surface of the well cap cover 20 and the upper flat surface of the peripheral flange 14 to provide a seal thereat.

The top wall 21 of the well cap cover 20 is provided with an internally threaded boss 29 which projects upwardly from the central portion thereof. The boss 29 communicates with the interior of the cover and is adapted 45 to threadedly engage a vent pipe when a vent pipe is used to vent the interior of the well casing with the exterior. In this regard, in some areas it is required that the interior of the well casing be vented to the exterior and this is accomplished by securing a vent pipe to the well cap cover device. In the event that no such venting requirement is necessary, then the threaded boss may be effectively closed by a threaded plug.

Suitable sealing means are provided for forming a seal between the well cap base 12 and the exterior surface of the well casing 11 and this means includes an annular sealing element 30 formed of a suitable resilient yieldable material, such as neoprene, rubber or the like, which has

the diameter slightly smaller than the exterior diameter of the well casing 11. With this arrangement, the annular sealing element 30 may be positioned in engaging relation with the exterior surface of the well casing as best seen in FIG. 2, and this is accomplished by stretching the sealing element slightly. Thereafter, when the well cap base 12 is positioned upon the well casing 11, the inner circumferential surface 18 of the cylindrical flange 17 engages the sealing element 30 adjacent the lower portion of this innertapered surface as best seen in FIG. 3. As the well cap base 12 is urged downwardly, the sealing element 30 will be rolled or pushed downwardly of the well casing 11 and will also be progressively urged upwardly with respect to the innertapered surface 18. When the well cap base 12 is disposed in place, the annular sealing element 30 will be positioned against the downwardly facing shoulder 19 so that a very tight, snug, compressed seal will be formed thereat.

The flange 17 is provided with a plurality of radially extending circumferentially arranged threaded openings 31 therein each accommodating a set screw 32 which may be tightened into place against the exterior surface of the well casing 11. With this arrangement, the well cap base may be very quickly and easily positioned in mounted relation on the upper open end portion of the well casing and may be positively but releasably locked in place. The annular sealing element and its coaction with the exterior surface of the well casing and the inner-circumferential surface of the flange 17 serve to form a highly effective seal between the well cap base and the well casing. The set screws 32 permit the well cap base to be applied and removed as desired.

It will therefore be noted that the well cap device 10 is formed of two essential parts, the well cap base and the well cap cover. The opening 16 in the well cap base accommodates the electrical conduits which extend downwardly into the well casing for connection to the electric pump. With the arrangement shown, the well cap cover may be removed to permit access to the interior of the well casing without requiring removal of the well cap base. This two piece construction of the well cap device not only facilitates ease in manufacture but facilitates ease in application and removal from a well casing. It is essential that an effective seal be provided between the well cap device and the well casing being closed, and the present arrangement not only provides a highly effective seal which may easily be applied but the present arrangement may be produced inexpensively.

From the foregoing description, it will therefore be seen that I have provided a novel well cap device which is not only of simple and inexpensive construction, but one which functions in a more efficient manner than any heretofore known comparable device.

It will, of course, be understood that various changes may be made in the form, details, arrangement and proportions of the various parts without departing from the scope of my invention.

What I claim is:

1. A well cap device for closing the upper open end of a cylindrical well casing, comprising an annular sealing element formed of a resilient yieldable material and having an inside diameter slightly smaller than the outside diameter of the well casing whereby the resilient sealing element may be stretched into engaging relation with the upper exterior surface of the well casing,

a well cap base having a circular opening therein slightly larger than the exterior diameter of the well casing to permit the well cap base to be positioned around the upper end of the well casing, said well cap base having an annular flange projecting downwardly from the lower surface thereof and being concentrically arranged with respect to said opening, said flange having an inner surface uniformly tapered downwardly from the upper end thereof, the inner surface of the flange at the upper end thereof having a diameter slightly larger than said opening to define a downwardly facing shoulder whereby when said well cap base is applied to the well casing, the tapered inner surface of said flange progressively compresses the sealing element against the outer upper surface of the well casing and against said shoulder of said well cap base as the latter is urged progressively downwardly along the well casing,

a concavo-convex well cap cover positioned in engaging relation on said well cap base so that the concave surface is disposed downwardly, and means for releasably securing said well cap cover to said well cap base.

2. A well cap device as defined in claim 1 wherein said means for securing said well cap base to the casing includes a plurality of threaded openings in said flange, and a plurality of threaded elements each threadedly engaging one of said threaded apertures in said flange and each threaded element engaging the exterior surface of the well casing.

3. The well cap device as defined in claim 1 wherein said well cap base is of oval configuration and said opening therein is offset with respect to the center thereof.

4. The well cap device as defined in claim 1 wherein said well cap base has an upwardly projecting relatively shallow peripheral flange integrally formed therewith and presenting a flat upper surface, a sealing element interposed between said upper peripheral flange and the lower peripheral edge of said cover to form a seal thereat.

5. The well cap device as defined in claim 1 wherein said means for securing said well cap cover to said well cap base comprises a plurality of threaded openings in the peripheral marginal portion of said well cap base, a plurality of peripheral openings in said well cap cover each being disposed in registering relation to one of said threaded openings in said well cap base when the cover is positioned upon said well cap base, and a plurality of threaded elements extending through said registering openings and threadedly engaging the threaded apertures in said well cap base whereby said cover may be removed from said well cap base without requiring removal of the base from the well casing.
